UNITED STATES PATENT OFFICE.

RAY W. SCOTT, OF NEW YORK, N. Y., ASSIGNOR, BY DIRECT AND MESNE ASSIGNMENTS, OF TWO-FIFTHS TO SCOTT PLAYER ACTION CO., OF RACINE, WISCONSIN, A CORPORATION OF ILLINOIS, AND THREE-FIFTHS TO THE NORTHERN TRUST COMPANY, OF CHICAGO, ILLINOIS, A CORPORATION OF ILLINOIS, TRUSTEE.

PUMPING SYSTEM FOR PLAYER-PIANOS.

1,389,323.

Specification of Letters Patent. Patented Aug. 30, 1921.

Application filed September 18, 1919. Serial No. 324,379.

To all whom it may concern:

Be it known that I, RAY W. SCOTT, a citizen of the United States, residing at New York city, State of New York, have invented a certain new and useful Improvement 5 in Pumping Systems for Player-Pianos, of which the following is a specification.

My invention relates to pumping systems for player pianos and like mechanism and 10 the object of the invention is to provide means whereby the operator may, at will, accentuate any single note or group of notes by merely exerting a sudden pressure upon the treadle of either of the pumps. It is 15 well understood by those skilled in the art that a note will be loud or soft in accordance with the degree of tension within the player action; and in carrying out my invention I have provided means for suddenly 20 raising the tension within the player action by devising mechanism whereby the operator, by exerting a sudden stroke of extra force upon either treadle, may quickly raise the tension within the player action without 25 waiting to raise the tension throughout the entire pumping system. My pumping system includes the usual exhaust pumps and storage reservoirs but according to my invention it is not necessary to raise the tension 30 to the desired degree throughout the entire pumping system. The reservoirs may be temporarily cut off and the tension from the pumps applied direct to the player action. In other words, in my mechanism the 35 operator may, by suddenly pressing upon the treadles, short circuit the reservoirs, so to speak, and thus immediately get the benefit in the player action of the increased tension. In the form shown, I accomplish 40 this by interposing a normally open valve between the exhaust pump and the reservoir and arrange to close this valve by means of a diaphragm which becomes effective when the pump tension is suddenly 45 raised.

Another object of the invention is to provide means for tempering or limiting the intensity of the blow of the hammer on the strings. For this purpose I have, according 50 to the design shown, backed up the valve by a spring capable of yielding when the pump tension exceeds a preordained minimum.

I accomplish my objects by the mechan-

ism illustrated in the accompanying drawings, in which,

55

Figure 1 is a front elevation in which the preferred commercial form of my invention is installed.

Fig. 2 is a plan section on the line 2—2, Fig. 1.

60

Fig. 3 is a sectional detail of the diaphragm and tempering spring and associated parts.

Fig. 4 is a sectional view analogous to Fig. 2 showing a simplified form of the invention:—especially as to the arrangement of the wind channels.

65

Like numerals denote like parts throughout the several views.

For commercial and practical reasons the 70 design shown in Figs. 1, 2, and 3 is preferable to the design shown in Fig. 4. The chief reason is that the valve mechanism is thus more readily accessible, which facilitates inspection and repairs. This form 75 will first be described, after which I will describe the form shown in Fig. 4 which is somewhat simpler and renders the principle of operation more obvious.

The player action and the pumping system 80 which embodies my invention are adapted to be installed in the piano case 1. The player action itself need not be described, as any standard type may be employed. It will be sufficient for the present purpose to 85 say that the tension for operating the player action is conveyed to it through the usual tube or wind way 2, a fragment of which is indicated in the drawing. It will be understood that, as usual, the loudness of the 90 tone will tend to increase and decrease in accordance as the tension in tube 2 increases or decreases.

My pumping system is provided with the usual exhaust pump or "feeders" 4, 4, operated by means of the usual foot pedal mechanism 5, 5. These pumps or feeders serve to exhaust air from a channel or windchest 6, in the manner well known in the art. Tube 2 communicates directly with this channel 100 and hence there is intimate connection between the exhaust pumps and the tube. Storage reservoirs 7, are provided, these being constructed in the usual manner and serving the usual purpose.

105

According to the design shown in Fig. 2,

I provide a chamber 8, and for the sake of identification shall refer to this as a "storage" chamber and to the channel 6 as a "primary" chamber. One wall 9 of the 5 storage chamber has a port 10 leading to a valve chamber 11. This valve chamber is, however, in reality a portion of the primary chamber 6 as it is at all times in communication with it. A duct 12 connects the 10 valve chamber with the primary chamber 6. A duct 13 connects the storage chamber 8 with the reservoir 7. The port 10 is controlled by a valve 16 which is mounted upon a lever 17 and normally held open by a 15 spring 19 or in any other suitable manner. The lever is pivoted to a stationary block 20. The accent valve 16 is controlled by a diaphragm 23 shown in detail in Fig. 3. This diaphragm is stretched over an opening 20 24 in wall 9 and is backed up by a disk 26 fastened to a stem 27. Said stem passes loosely through an opening in lever 17 and is provided with a collar 28 fastened to the stem on the far side of the lever. A helical compression spring 30 is interposed between the disk and the lever. The result is that when the diaphragm moves outward toward the lever, it will, acting through the medium of the disk and spring, urge the 30 lever in a direction to close the valve.

Operation: In practice, if the pumping system is operated in a normal manner the pumps 4 will exhaust air from the primary chamber and create air tension therein. As 35 the tube 2 is connected to said primary chamber, air tension will also be created in the tube and cause the normal operation of the player action. As the accent valve 16 is normally open, and as the storage chambers 40 7 are consequently normally in communication with the primary chamber through the ports and passages 10, 12 and 13, the tension in the storage chamber will normally correspond substantially to the tension in 45 the primary chamber and tube 2. But the closing of the valve will shut the reservoir off from the primary chamber; and it is evident that if this valve is shut the tension in the tube will respond much more quickly 50 to the variation in tension in the primary chamber. As a matter of fact, with the storage reservoirs thus cut off or "short circuited" by the closure of valve 16, the tension in tube 2 will, practically speaking, 55 vary instantly in accordance with the variations in tension in the primary chamber. As the primary chamber 6 and valve chamber 11 are at all times in communication, they are, pneumatically speaking, one and the 60 same thing. In the form shown in Fig. 4, the valve chamber, as such, is omitted and the valve is located in the primary chamber. But still referring to the form shown in Fig. 65 2, if the operator suddenly exerts extra pressure upon either of the treadles 5, the tension

will be suddenly raised in the primary chamber, and consequently in the valve chamber, and this tension acting upon the diaphragm tends to draw it in a direction to close the valve. With the valve closed and the storage reservoir 7 thus cut off, this sudden increase in the tension in the primary chamber will immediately have its effect on the player action and will accent the note or group of notes being played at the time. Thus the 70 operator has instant control through the treadles and may accent any note or group of notes at will by simply making a sudden stroke upon either or both of the treadles. The loud playing may be continued as long 75 as desired by merely keeping the tension in the primary chamber materially above the tension in the storage reservoir. As soon as the difference in tension is permitted to decrease sufficiently, the valve will return to 80 open position and the intensity of the tone will return to normal.

Undue loudness of tone or intensity of the blow of the hammers is prevented by the yielding connection between the disk 26 and 85 the lever 17. It will be evident that if the operator permits the tension in the chambers 6 and 11 to rise too high, relatively to the tension in the reservoir 7, the tension in valve chamber 11 will open the valve in spite 90 of the tendency of the spring 30 to keep it closed. In other words, the yieldable connection between the accent valve and the diaphragm which operates it prevents the difference in tension to rise above a predetermined maximum and it will be understood, of course, that the storage reservoirs are furnished, as well known in the art, with safety valves which will prevent the tension in said reservoir from exceeding a 95 predetermined maximum.

From the foregoing it will be evident that as a result of my invention the operator, by properly manipulating the treadles themselves and without the assistance of any 100 other mechanism, may accent any note or group of notes at will and at the same time excessive accentuation is automatically guarded against.

The practical advantage arising from 105 the form shown in Fig. 2 is that it makes it possible to mount the valve mechanism on the front of the wall 9 where it may be readily reached for inspection or repairs. The front of the valve chamber is closed by 110 a removable cover 35, and by simply removing this cover, the parts are readily accessible from the front. In the form shown in Fig. 2 the valve chamber, as a separate 115 element, is omitted and the port 10 is formed in a wall 9a which forms the front of the primary chamber 6 and the back of the storage chamber 8a. Said storage chamber communicates with the reservoir 7 through a 120 passage 13a. The valve mechanism is 125 130

mounted within the primary chamber 6 but its construction and principle of operation remains unchanged. In this simplified form shown in Fig. 4 the rear wall of the 5 primary chamber has an opening 40 formed in it to afford access to the valve mechanism. This opening is normally closed by means of a cover 41.

Having thus described my invention what 10 I claim as new and desire to secure by Letters Patent, is:—

1. A pumping system for player actions having an exhaust pump, a storage chamber having a wall separating it from said pump, 15 the wall having a port passing through it, a tube communicating with the player action for actuating it, said tube communicating with the pump and communicating with the storage chamber through said port, a 20 valve for controlling said port whereby when the valve is closed the tension in the duct will be generated directly from the exhaust pump and when said valve is open the tension in said duct will be modified by the 25 degree of tension in said storage chamber, and a diaphragm responsive to sudden changes of tension in said exhaust pump for controlling the position of said valve.

2. A pumping system for player actions 30 having a primary chamber, an exhaust pump for creating tension therein, a storage chamber having a wall, the outer surface whereof assists in confining the body of air in the primary chamber, the wall having a port 35 passing through it, a tube communicating with the player action for actuating it, said tube communicating with the primary chamber and communicating with the storage chamber through said port, a valve for controlling 40 said port, said wall having a second opening, a diaphragm over said second opening, and means operated by said diaphragm for actuating said valve.

3. A player piano action having a high tension 45 primary chamber communicating with the key operating mechanism, a pump for exhausting the air from said chamber, a storage chamber, a wall having on one side the high tension and the other side the 50 low tension air, said wall having a port in it for normally equalizing the air tension in the two chambers, a valve, yieldable means for normally holding said valve open, and pneumatic means exposed on opposite sides 55 to the high and low tension and adapted to close the valve in case of a sudden rise in tension in the primary chamber.

4. A pumping system for player actions 60 having a duct leading to the player action for operating it, a storage reservoir for withdrawing air from said duct, a pump adapted to withdraw air both from the duct and the reservoir, valve mechanism for disconnecting the reservoir from the duct, and a dia- 65 phragm adapted to be influenced by the air

tension created by the pump for controlling said valve mechanism.

5. A pumping system for player actions having a duct leading to the player action for operating it, a storage reservoir for withdrawing air from said duct, a pump adapted to withdraw air both from the duct and the reservoir, a valve for disconnecting the reservoir from the duct, and yieldable means for regulating the difference in tension 70 between the air in said duct and the air in said reservoir. 75

6. A pumping system for player actions having a duct leading to the player action for operating it, a storage reservoir for withdrawing air from said duct, a pump adapted to withdraw air both from the duct and the reservoir, a valve for disconnecting the reservoir from the duct, means adapted to be influenced by the air tension created by 80 the pump for closing said valve when the tension is suddenly increased by the pump, and yieldable means for holding said valve to its seat, whereby when the tension created by the pump becomes excessive it will cause 85 the valve to recede from its seat. 90

7. A pumping system for player actions having a primary chamber, an exhaust pump for creating tension therein, a storage chamber having a wall separating it from the 95 primary chamber, the wall having a port passing through it, a tube communicating with the player action for actuating it, said tube communicating with the primary chamber and communicating with the storage 100 chamber through said port, a valve for controlling said port, said wall having a second opening, a diaphragm over said second opening, and a yieldable connection between 105 said diaphragm and said valve. 105

8. A pumping system for player actions having a duct leading to the player action for operating it, a primary chamber communicating with said duct, a pump for creating tension in said primary chamber, a storage chamber having a port leading to the primary chamber, a valve adapted to control said port, a diaphragm responsive to the difference in tension between the primary chamber and the storage chamber, and connections between said diaphragm and said valve whereby when the tension in the primary chamber exceeds the tension in the storage chamber, said diaphragm element will be caused to move in a direction to close 110 the valve. 115

9. A pumping system for player actions having a duct leading to the player action for operating it, a primary chamber communicating with said duct, a pump for creating tension in said primary chamber, a storage chamber having a port leading to the primary chamber, a valve adapted to control said port, a movable element responsive to the difference in tension between the 120 125 130

primary chamber and the storage chamber, connections between said movable element and said valve whereby when the tension in the primary chamber exceeds the tension in the storage chamber, said movable element will be caused to move in a direction to close the valve, said valve being of the puppet type and so placed that an increase in tension in the primary chamber tends to open said valve, and yielding connections between said valve and said movable element.

10. A pumping system for player actions having a primary chamber, an exhaust pump for creating tension therein, a tube communicating with the player action for actuating it, said tube also communicating with the said primary chamber, a storage chamber, a valve chamber in front of said storage chamber and having a port leading to the storage chamber, said tube communicating with said storage chamber through said valve chamber and port, a valve for controlling said port, and a movable element responsive to variations in tension between the valve chamber and the storage chamber for actuating said valve, said valve chamber having a removable cover in front and the valve and the movable element being located in said valve chamber whereby they are readily accessible from the front when the cover is open.

15. A pumping system for player actions having a primary chamber, an exhaust pump for creating tension therein, a tube communicating with the player action for actuating it, said tube also communicating with said primary chamber, a storage chamber, a valve chamber in front of said storage chamber and having a port leading to the storage 20 chamber, said tube communicating with said valve chamber and port, a valve for controlling said port, and a diaphragm responsive to variations in tension between the valve chamber and the storage chamber for actuating said valve.

25. A pumping system for player actions having a primary chamber, an exhaust pump for creating tension therein, a tube communicating with the player action for actuating it, said tube also communicating with said primary chamber, a storage chamber, a valve chamber in front of said storage chamber and having a port leading to the storage 30 chamber, said tube communicating with said

storage chamber through said valve chamber and port, a valve for controlling said port, and a movable element responsive to variations in tension between the valve chamber and the storage chamber for actuating said valve, said valve chamber having a removable cover in front and the valve and the movable element being located in said valve chamber whereby they are readily accessible from the front when the cover is open.

35. A pumping system for player actions having a primary chamber, an exhaust pump for creating tension therein, a tube communicating with the player action for actuating it, said tube also communicating with said primary chamber, a storage chamber, a wall having on one side the high tension and the other side the low tension air, said wall having a port in it for normally equalizing the air tension in the two chambers, a valve, yieldable means for normally holding said valve open, and pneumatic means exposed on opposite sides to the high and low tension and adapted to close the valve in case of a sudden rise in tension in the primary chamber, said valve opening toward the high tension primary chamber and the connection between the valve and said pneumatic means being yieldable whereby the valve may open against the force of said pneumatic means in case the difference in tension between the two chambers becomes excessive.

In witness whereof I have hereunto subscribed my name.

RAY W. SCOTT.
